UNITED STATES PATENT OFFICE.

FRANK B. PARKER AND CHARLES U. AUSTIN, OF ROCHESTER, NEW YORK.

LUBRICATING SYSTEM FOR VALVE STEMS.

Application filed March 13, 1922. Serial No. 543,513.

To all whom it may concern:

Be it known that we, FRANK B. PARKER and CHARLES U. AUSTIN, citizens of the United States of America, residing at Rochester, in the county of Monroe and State of New York, have invented certain new and useful Improvements in Lubricating Systems for Valve Stems, of which the following is a specification.

10 The object of this invention is to provide means whereby lubricating oil from the crank case of an internal combustion engine may be automatically fed to the valve stem guides of the intake valves of the engine to lubricate the bearings of the valve stems.

Another object of this invention is to surround the valve stem with a film of oil and maintain this film so that it will form a 20 packing surrounding the stem and greatly reduce the leakage of air past the valve stem into the valve chamber and manifold of the engine.

These and other objects of this invention 25 will be fully illustrated in the drawing, described in the specification and pointed out in the claims at the end thereof.

In the accompanying drawing:

Figure 1 is a detail sectional view of a 30 valve, valve chamber and portion of the crank casing, showing the valve operating mechanism of an internal combustion engine.

Figure 2 is a detail view of a valve provided with the oil feeding means.

In the several figures of the drawing like reference numerals indicate like parts.

In the construction of internal combustion engines especially the four cycle type 40 of engines no provision is made at the present time to automatically lubricate the valve stem guides of the intake valves.

This lubrication of the valve stem guides is made possible by my present invention in 45 which the partial vacuum created in the valve chamber and intake manifold of the engine is utilized to constantly feed sufficient lubricating oil from the crank casing to the valve stem guides and surround the 50 valve stem with an oil film.

The moving and rotating parts mounted in the crank casing 1 of the engine are kept lubricated by splashing or pumping the lubricating oil contained in the bottom of 55 the casing to these parts. In this way some of the oil is fed to the periphery of the

valve cam 2 on the rotation of which the valves 3 are operated. The movement of the cam is communicated to the valve stems 4 thru the tappets 5. These tappets are 60 mounted to slide in a guide sleeve 6 that is suitably threaded or otherwise fastened into the top of the crank casing 1.

The tappet is made up of a hollow stem of which the lower end is flattened out to form 65 a shoe 5^A thereon. This shoe is adapted to rest on the periphery of the cam 2 and rides on it as the cam is rotated. In the shoe is provided the small opening 7 which leads into the hollow portion of the tappet valve 70 5. The length of the tappet is made adjustable by means of the adjusting screw 8. This screw is threaded into the top of the tappet with a locknut 9 provided thereon to lock the adjusting screw to the tappet 75 and make the tappet the proper length for the operation of the valve.

The valve 3 opens and closes the opening in the top of the valve chamber 10, and a valve seat 11 is provided surrounding this 80 opening on which the valve 3 is seated. The valve stem 4 of the valve 3 is mounted to slide in a suitable guide or bearing 12 which is threaded into the valve chamber 10 or otherwise suitably fastened thereto. This 85 guide projects below the valve chamber and is surrounded by the valve spring 13. The spring 13 extends between the shoulder 14 formed on the guide 12 and the washer 15 held in place on the valve stem 4 near the 90 lower end thereof. The washer 15 is held in place on the valve stem by means of the pin or key 16 which passes diametrically through the stem and projects from two sides thereof. Instead of fastening the 95 washer 15 to the valve stem by means of the pin 16 the valve stem may be provided with a circular groove 16^A in which the washer can be suitably held in place. This type of valve is illustrated in Figure 2.

The expansion of the spring 13 normally forces the valve down on the valve seat 11 to close the top of the valve chamber 10. The intake manifold through which the fuel passes to the cylinders leads into the valve 105 chamber 10 so that the valve 3 controls the passage of the fuel from the manifold to the inside of the cylinder. During the operation of the engine a partial vacuum is created in the cylinders of the engine. This 110 partial vacuum is extended to the valve chamber and intake manifold on the lifting

of the valve 3 and operates to draw the fuel into the engine. The partial vacuum thus created in the valve chamber 10 and manifold is utilized to draw the lubricating oil 5 from the crank casing to the valve stem guide as will now be described.

The lower end of the valve stem has a vertical duct 17 provided therein which leads from the lower end of the stem to a 10 horizontal duct 18. This horizontal duct passes diametrically through the stem and is located in the valve stem 4 at a point where the stem is surrounded by the guide 12 preferably near the lower end of this 15 guide. In order to make the vertical duct continuous and prevent its being obstructed by the pin 16, the pin 16 is encircled by a groove 19 which reduces its diameter at the point where the pin passes through the vertical duct 17. This forms a circular channel around the pin 16 and connects the lower part of the vertical duct 17 with the upper part thereof. In the type of valve illustrated in Figure 2 where the washer 15 is 20 supported in the groove 16^a, the vertical duct is not obstructed.

The lower end of the valve stem rests on top of the adjusting screw extension 8 of the tappet 5. This adjusting screw has a 30 vertical duct 20 provided therein which leads from the hollow center of the tappet to the outer end thereof to form a continuation of the vertical duct 17 in the valve stem 4. A continuous duct thru the tappet and valve stem is thus formed which leads from the periphery of the cam 2 in the crank casing 1 to the horizontal duct 18 in the portion of the valve stem 4 surrounded by the guide 12.

40 The partial vacuum in the valve chamber 10 and the manifold creates a proportional vacuum between the valve stem guide and the valve stem, and this vacuum is communicated thru the vertical duct in the valve stem and tappet to the opening 7 in the shoe of the tappet so that some of the lubricating oil adhering to the periphery of the cam is picked up and drawn thru the opening 7 to the wicking 21 contained in 45 the hollow center of the tappet 5. From there the oil is drawn thru the vertical duct 20 in the adjustable extension of the tappet into the vertical duct 17 in the valve stem 4. In this duct 17 the oil rises until it reaches the horizontal duct 18 thru which it passes out from the center of the valve stem into an annular channel 22 surrounding the valve stem. From the annular channel 22 the oil is drawn against the walls of the 50 valve guide 12 which it thus keeps constantly lubricated. In lubricating the guide 12 in the manner above pointed out a thin film of oil is formed around the valve stem forming a packing around it and this reduces a leakage of air between the valve 55

stem and the walls of the valve stem guide to a minimum so that the engine can be throttled and regulated without any interference from air leaking past the valve stems into the manifold valve chamber.

70 The amount of lubricating oil passing through the tappet 5 to the valve stem guide is regulated by the amount of wicking contained in the hollow center of the packet. Thus a large amount of wicking tightly packed into the tappet will allow less oil to pass therethrough than will a smaller amount of wicking not so tightly packed into the tappet.

75 We claim:

1. In a valve for internal combustion engines, the combination of a valve stem having a vertical duct leading into the free end thereof and branching out on the sides thereof and means for connecting said vertical duct with the inside of the crank casing of the engine.

80 2. In a lubricating system for lubricating the valve stem guide of internal combustion engines, the combination of a valve, a valve stem formed integral with said valve, said valve stem having a duct leading up from the end thereof and branching out on the sides of said valve stem within the valve stem guide and means for operating said valve by abutting the end of said valve stem at the entrance of said duct.

85 3. In a lubricating system for the valve stem guide of an internal combustion engine, the combination of a valve stem having a vertical duct leading up from the free end and branching out of the sides thereof within the valve stem guide, a tappet for operating said valve stem, said tappet having a duct leading therethrough in line with the duct in said valve stem.

90 4. In an internal combustion engine, the combination of a valve chamber, a valve operating in said valve chamber, a valve stem for lifting said valve, a valve stem guide leading from said valve chamber, said valve stem having a vertical duct leading up from the free end and branching out of the sides thereof within said valve stem guide, a crank casing, a cam mounted to rotate in said crank casing, a tappet mounted to slide in said crank casing, said tappet having a duct leading through the center thereof, said tappet making contact with the end of said valve stem with one end thereof and bringing its vertical duct in line with the vertical duct of said valve stem, the other end of said tappet making contact with said cam in said crank casing, means to splash oil on to the periphery of said cam and means to force the oil from the periphery of said cam through the ducts in said tappet and said valve stem to lubricate said valve stem guide.

100 5. In an internal combustion engine, the

- combination of a valve chamber, a valve operating in said valve chamber, a valve stem for lifting said valve, a valve stem guide leading from said valve chamber, said 5 valve stem having a vertical duct leading up from the free end and branching out of the sides thereof within said valve stem guide, a crank casing, a cam mounted to rotate in said crank casing, a tappet mounted to slide in said crank casing, said tappet having a duct leading through the center thereof, said tappet making contact with the end of 10 said valve stem with one end thereof and bringing its vertical duct in line with the vertical duct of said valve stem, the other 15 end of said tappet making contact with said cam in said crank casing, means for creating a partial vacuum in said valve chamber to draw the lubricating oil from the periphery of said cam through the ducts 20 in said tappet and said valve stem into said valve stem guide.
6. In a lubricating system for the valve stem guide of an internal combustion engine, the combination of a valve stem having 25 a vertical duct leading up from the free end thereof, a tappet for operating said valve stem, said tappet being hollow in the center, wicking placed into the hollow center 30 of said tappet, and means to draw lubricat-
- ing oil into the wicking in said tappet and from said wicking through the duct in said valve stem into said valve stem guide.
7. The method of lubricating the wall of a guide sleeve for a valve stem which consists 25 in providing a duct leading from the crank case of an engine thru the operating member of the valve stem and through a portion of the valve stem to the wall of the guide sleeve, creating a partial vacuum above said 40 valve stem and guide sleeve to draw the lubricant from the supply in the crank case of the engine into the guide sleeve for lubricating purposes.
8. The method of lubricating the wall of 45 a guide sleeve for a valve stem which consists in providing for the escape of a small but continuous quantity of oil from the crank case of an engine, creating a partial vacuum around the valve stem and allowing 50 the partial vacuum to draw the escaped oil through a duct in the valve stem into the guide sleeve by locating the end of the duct in the valve stem over the escaped oil from the crank case.

55
In testimony whereof we affix our signatures.

CHARLES U. AUSTIN.
